UNITED STATES PATENT OFFICE.

JOHN A. H. DRESSEL, OF BROOKLYN, NEW YORK.

DESIGN FOR A TARGET.

SPECIFICATION forming part of Design No. 14,355, dated October 23, 1883.

Application filed July 6, 1883. Term of patent 14 years.

To all whom it may concern:

Be it known that I, JOHN A. H. DRESSEL, a citizen of the United States, residing at Brooklyn, in the county of Kings and State of New York, have invented and produced a new and original Design for Targets, of which the following is a specification, reference being had to the accompanying drawings, forming a part thereof.

10 The design which I have produced is illustrated in the accompanying drawing, in which—

15 The letters A B designate the two or more concentric rings, and C the circular bull's-eye, of an ordinary target.

20 D D are radial lines extending from or near the bulls-eye C to or nearly to the outer ring, A. The lines D D are twelve in number, and are placed at equal distances apart, after the manner of the hour-marks on an ordinary clock or watch dial. In addition to the lines are numbers from 1 to 12, which are placed near the said lines at their ends, as shown, or in such manner that the eye may readily see to what 25 hour-mark of an ordinary clock any one of the lines D D corresponds.

Heretofore targets have been made with an arbitrary number of circles, squares, or similar figures around a bull's-eye, and one or more lines drawn diametrically across them. The 30 essential feature of my design, however, is the arrangement across the face of the target of lines or marks D D, corresponding in number and position to the hour-marks of a clock-dial.

35

What I therefore claim is—

1. The design for targets, consisting of circles or rings around a central bull's-eye, with lines or marks corresponding in number and position to the hour-marks of a clock-dial, substantially as herein shown and described. 40

2. The design for targets, consisting of the central bull's-eye, C, concentric circles A B, and radial lines D D, numbered from 1 to 12 consecutively, as herein shown and described. 45

In testimony whereof I have hereunto set my hand this 2d day of July, 1883.

JOHN A. H. DRESSEL.
